UNITED STATES PATENT OFFICE.

HARRY G. NORWOOD, OF BALTIMORE, MARYLAND, ASSIGNOR TO WILLIAM ANDREW FULD, OF BALTIMORE, MARYLAND.

DESIGN FOR A SEAT-BODY FOR CHILDREN'S VEHICLES.

58,041.

Specification for Design.

Patented May 31, 1921.

Application filed October 8, 1920. Serial No. 415,704. Term of patent 14 years.

To all whom it may concern:

Be it known that I, HARRY G. NORWOOD, a citizen of the United States, residing at Baltimore, State of Maryland, have invented a new, original, and ornamental Design for a Seat-Body for Children's Vehicles, of which the following is a specification, reference being had to the accompanying drawing, forming part thereof.

Figure 1 is a side elevation of a seat body for children's vehicle showing the seat body in full lines, and

Fig. 2 is a top plan view thereof.

I claim:

The ornamental design for a seat body for children's vehicles as shown.

HARRY G. NORWOOD.
